CLAIM

The ornamental design for a filter element, as shown and described.

DESCRIPTION

FIG. 1 is first perspective view of a filter element showing my new design;

FIG. 2 is second perspective view thereof;

FIG. 3 is third perspective view thereof;

FIG. 4 is a front view thereof;

FIG. 5 is a back view thereof;

FIG. 6 is a left side view thereof;

FIG. 7 is a right side view thereof;

FIG. 8 is a top plan view thereof;

FIG. 9 is bottom plan view thereof;

FIG. 10 is an enlarged view of portion of FIG. 2; and,

FIG. 11 is an enlarged view of portion of FIG. 3.

The broken lines in the drawings depict portions of the filter element that form no part of the claimed design.
